UNITED STATES PATENT OFFICE.

TEOFIL ZLYDASZYK, OF CHICAGO, ILLINOIS.

AUTOMATIC VALVE-CLOSING DEVICE FOR GAS PIPES.

Application filed December 3, 1924. Serial No. 753,654.

To all whom it may concern:

Be it known that I, TEOFIL ZLYDASZYK, a citizen of Poland, residing at Chicago, in the county of Cook and State of Illinois, have invented certain new and useful Improvements in Automatic Valve-Closing Devices for Gas Pipes, of which the following is a specification.

My invention relates to automatic valve closing devices for gas pipes and its principal object is the provision of thermostatic means for actuating the mechanism for closing the auxiliary valve.

Another object of the invention is to adapt the known property of metals, viz. expansion and contraction under varying temperatures for operating suitable mechanism for closing the valve in a gas pipe when the supply of gas is discontinued due to any cause.

Should the flame be extinguished the gas would escape with the danger of asphyxiating the occupants of a room or dwelling, there being no safe means for automatically closing the valve, therefore, a further object of the invention is the provision of an auxiliary valve and means connected thereto for closing the same when the flame becomes extinguished due to any cause with the regular valve remaining open.

A still further object of the present invention is to provide means thermostatically operated for the purpose mentioned particularly adapted for use in kitchen gas stoves.

Another object of the invention is to provide signalling means connected with and actuated by the valve operating means for the purpose of assuring the occupants that the device is in an operative condition.

A still further object of the invention is the provision of means transmitting immediately the action of the thermostat to the respective device from the burner farther removed from its cooperating device as in a kitchen stove where one auxiliary valve closing device is provided for each burner and where the relative position of the devices in respect to their burners is not uniform.

With these general objects in view and others that will appear as the nature of the invention is better understood, the same consists in the novel construction, combination

and arrangement of parts hereinafter more fully described, illustrated in the accompanying drawings and pointed out in the appended claims.

In the drawings forming a part of this application, and in which like designating characters refer to corresponding parts throughout the several views.

Figure 1 is a top plan view of the device with cover removed, also showing top plan view of a burner with the grating removed;

Figure 2 is a cross-sectional view of a detail part of the invention taken on line 2—2 of Figure 1;

Figure 3 is a cross-sectional view on line 3—3 of Figure 1 with the cover and grating added;

Figure 4 is a longitudinal view through the platform and the cover showing part of the mechanism in elevation and part in section, the view being taken on line 4—4 of Figure 1;

Figure 5 is a top plan view of the stove with a number of burners and a like number of the present devices cooperating with the respective burners;

Figure 6 is a cross sectional view of a modified form of the invention which in its principal features resembles the form illustrated in Figure 3;

Figure 7 is a longitudinal sectional view of a part of the invention taken on line 7—7 of Figure 5;

Figure 8 is a cross sectional view through the auxiliary valve taken on line 8—8 of Figure 1; and

Figure 9 is a top plan fractional view showing a detail of the invention in its modified form taken on line 9—9 of Figure 6.

Coming to a more detailed description the invention is associated with a kitchen stove 10 having a common type burner 11 to which gas is supplied by pipe 12 and main pipe 13. Said pipe 12 is provided with a valve casing 13 within which are positioned two valves, viz. a regular valve 14 and an auxiliary valve 15, this latter valve being intended to be operated by the mechanism constituting the present invention. Said mechanism, positioned upon platform 16, embodies an upper lever 17 and a lower lever 18. Near its end adjacent pipe 12 the said upper lever is

pivoted to the platform as at 19 (Fig. 1), while the lower lever is pivoted near its outer end to said platform as at 20.

Each of said pivot points embodies a screw head 21 (see Fig. 2), a relatively thick shank 22 passing through an aperture made in each lever, and screw point 23 which passes through said platform 16 and is adapted to receive nut 24 therebelow. Head 21 being wider than the shank prevents any upward creeping movement of the levers.

At their outer ends the levers are joined by means of pivotal connecting link 25. The lower lever 18 is longer than the upper lever and at its inner end carries a rack bar 26 which is pivotally imbedded within the lever by its enlarged head 27. Leaf spring 28 is affixed by its upper end to the end of the lever 18 and presses upon the back of said rack bar. The opposite edge of the rack bar is provided with teeth 29 and has cam portion 30 which cooperates with pin 31 projecting from the platform.

Coil spring 31' presses at all times against the side of lever 18 and lug 32 projecting from said side prevents the displacement of said spring.

The auxiliary valve 15, best illustrated on Figure 8, comprises a downwardly tapering valve stem 32'. For opening the valve a handle 33 is provided upon said stem. The lower reduced end of the stem is of a square formation in cross section for rigidly securing thereon disk 34. Said lower end of the stem is provided with a threaded bore for affixing said disk upon said end by means of screw 35, the screw head being entirely enclosed within socket 36 made in said disk. Washer 37 fitted upon said square end of the stem remains interposed between said disk 34 and the valve casing 13. It will be seen that by turning the handle 33 to operate the valve, disk 34 will be revolved with the stem. A portion of the periphery of said stem adjacent its upper end is threaded as at 38 for receiving ring 39 which is positioned in a circular groove made in the casing. For the purpose of removing or adjusting said ring by a face spanner a pair of holes 40 is made therein. The purpose of said ring is to prevent biting of said tapered valve stem into the valve casing.

Said disk 34 has a reduced portion 41 and a resulting off-set portion 42. Pin 43 is projecting vertically from said off-set portion and on a line substantially diametrically opposite from said pin the periphery of the disk is provided with teeth 44, and more or less at an intermediate point on the periphery a horizontal pin 45 projects therefrom. Coil spring 46 is secured by its one end to said pin and the other end thereof is anchored to the platform 16 by means of screw 47.

Lever 48 is pivoted at its central portion

to the support 49 projecting from the platform. The rear end of said lever is under upward tension by spring 50. Operating rod or button 51 is pivotally secured to the rear end of said lever. Tongue 52 extends rearwardly from the rear end of said lever and cooperates with bell 53 for the purpose hereinafter described.

A thermostatic rod 54 is imbedded in stove wall 55 and by the other reduced end is loosely position in socket 56 made in the adjacent side of lever 17 at the inner end thereof. Grating 56' remains above said rod.

Figure 1 illustrates the position of the device above the plane of the burner, while the modified form of the invention, illustrated on Figure 6, assumes the device to be below the plane of the burner. In that latter instance an upright standard 57 integrally formed with lever 17 is provided, and a series of sockets 58 are formed therein. A plurality of said sockets is for convenience merely as the rod may be positioned in any one of said sockets depending upon the relative position of the burner and of the rod in respect to the device.

A cover 59 is provided for enclosing the device with the exception of handles of valves 14 and 15 and button 51, all of which project through said cover, the cover being secured to the platform 16 and to the stove by any suitable means. The modified form of the invention illustrated on Figure 6, has cover 60 which is likewise secured to the platform 16 and by means of brace 61 is attached to the stove. By bracket 62 which is affixed to the wall of the stove the platform is supported.

Figure 5 illustrates four of the present devices with the cover removed and four burners disposed on top of the stove with the grating removed, the devices being indicated generally by letters A, B, C and D, and the burners with which said devices operate are marked by A', B', C' and D', respectively. Bar 63 is longitudinally positioned over the top of the stove and affixed thereto by screws 64. Rods 54^a and 54^b cooperating with burners A' and D' are positioned by their rear ends in the apertures made in said bar, said apertures being threaded for receiving screws 65 by means of which said rods are properly adjusted in respect to the levers 17 in the devices A and D. Nuts 66 upon said screws 65 prevent any creeping movement thereof under the expanding or contracting action of said rods under varying temperatures.

Since burners B' and C' are farther removed from their respective devices B and C and are not in alignment therewith the thermostatic action of rods 54^a and 54^b is transmitted to rods 67 and 68, respectively, which rods cooperate with levers 17 in the devices B and C. The expanding or con-

- tracting action of rod 54^b is transmitted to the rod 67 through the medium of plates 69 and 70 which are positioned in the cut-away portion in the bar 63 as illustrated on Figure 7. The outer end of each of said plates are rounded and do not abut the adjacent faces resulting in said cut-away portion in said bar 63. This arrangement is necessary in order that said plates may freely move within said cut-away portion and clear by said adjacent faces when actuated by rod 54^b. Each of said plates is pivoted on pins 71 and 72 which project from the bar 63. The inner end of plate 69 is reduced in thickness and has a projecting pin 73. The inner end of plate 70 is likewise reduced in thickness and forms a shackle 74 which overlies the reduced end of said plate 70. Said pin 73 and shackle 74 form interlocking means between the two plates, yet permitting the horizontal shifting movement of the plates on their pivots 71 and 72. The reduced end of rod 54^b is loosely positioned in socket 75 made in the adjacent edge of plate 69 at the outer end thereof. The reduced upper end of rod 67 is loosely positioned in socket 76 made in the opposite edge of plate 70 at its outer end, while the other end of said rod 54^b cooperates with lever 17 of the device B.
- Similar means as that described above is provided for the rods 54^c and 68, wherein plate 70' is associated with rod 54^c and plate 69' cooperates with rod 68, the plates being pivoted on pins 72' and 71', respectively, and have interlocking means at their inner ends consisting of pin 73' and shackle 74'. In this instance the rod 54^c is assumed as being expanded and pressing upon the outer end of plate 70' forcing the inner end thereof to move in the opposite direction and to assume an oblique position on its pivot point in respect to the bar 63. This shifting movement of the inner end of plate 70' causes the inner end of plate 71' to move in the same direction forcing the outer end of the last mentioned plate to move in the opposite direction which in turn exerts pressure on rod 68.
- Both rods 54^b and 54^c have the rear ends threaded and positioned in bores provided in the rear wall 77 of the stove. Nuts 78 prevent the displacement of said rods from their adjusted positions. For further guarding against the displacement of said rods screws 79 bear against the adjacent ends thereof and nuts 80 hold said screws in proper position.
- Having described the construction of the invention I come now to the description of the operation thereof with the understanding that the designating characters on Figure 1 denote the corresponding parts on all of the devices indicated by A, B, C, and D on Figure 5, and since the position of the several parts illustrated on Figure 1 is identical with that in the device B of Figure 5 the description of the operation of said last mentioned device will also cover the device illustrated in Figure 1.
- Device A illustrates the invention in its inoperative position with the regular valve 14 and the auxiliary valve 15 closed and no gas burning in burner A', and therefore with rod 54^a cool and contracted.
- To bring the device into an operative position the auxiliary valve 15 is opened by turning handle 33 in the direction of an arrow shown on Figure 1. While turning said handle the stem 32 and the disk 34 are rotated therewith in the same direction. Said handle should be turned sufficiently far until the off-set portion 42 of the disk is cleared away from the vertical path of movement of the forward end of lever 48, the reduced portion 41 of said disk permitting elevation of the forward end of said lever above said disk. When this is done the handle is held manually against the tension of spring 46 and by the other hand pressure is applied upon button 51 causing the elevation of the forward end of lever 48. When the manual hold on handle 33 is released the spring 46 causes a slight backward rotary movement of the disk until pin 43 comes in lateral engagement with the lever 48 which limits the further backward movement of the disk and consequently of the stem, and in such a manner the auxiliary valve is held open. When in that position lever 48 by its forward end rests upon the off-set portion 42 intermediately of said pin 43 and the edge of the said off-set portion as plainly shown on Figures 1 and 8. When the above operation is completed and the regular valve 14 is opened permitting the supply of the gas through pipe 12 to the burner B', the gas is then lighted in said burner heating rod 54 in Figure 1 or rod 54^b in Figure 5. It is observed that before rod 54 of Figure 1 is sufficiently expanded to exert any pressure upon lever 17, the rack bar 26, remaining in contact with pin 31 by its cam portion 30, is held away from the disk 34 and the teeth 44.
- Device C of Figure 5 illustrates the position of the mechanism when the gas in burner C' is lighted. There rod 54^c is assumed to be expanded and owing to its expansion under the influence of high temperature exerts a pressure upon rod 68 through plates 70' and 69' as already explained. This causes the shifting movement of the inner end of lever 18 and of the rack bar 26. Even a slight movement of said rack bar will cause the disengagement of the cam portion 30 from pin 31, and when said pin abuts the reduced portion of said rack bar, spring 28 pressing against the rack bar will cause teeth 29 to come into engage-

ment with teeth 44 on disk 34. A further expansion of the rod 54^a and a consequent further pressure on rod 68 will cause a further sliding movement of said rack bar 5 and a consequent turning of the disk 34 will be effected. This will cause the disengagement of the forward end of lever 48 from the off-set portion 42 of the disk 34 permitting said end to drop to the platform 10 owing to the pressure of spring 50 at the rear end of the lever. The rear end of the lever will become elevated causing tongue 52 to strike bell 53 and thus a signal will be given to the occupants of the room that the device is in a working condition. Device C on Figure 5 illustrates the forward end of lever 48 as being disengaged from the off-set portion 42 of the disk 34 and resting upon platform 16. Rack bar 26 is in engagement with the teeth upon said disk. As long as the gas burns and rod 54^a is expanded rack bar 26 will hold the auxiliary valve 15 open against the tension of the spring 46 permitting the continued flow of gas, said 20 rack bar being in engagement with the disk 34.

Should a further supply of the gas be shut off at the gas factory or interrupted owing to the low pressure or the flame become extinguished rod 54^a will gradually cool off and contract.

Device D on Figure 5 illustrates the position of the mechanism when rod 54^a has cooled off owing to the extinguishment of the flame in burner D' due to any cause. When the rod cools off the pressure on lever 17 is diminished and spring 31' pressing against lever 18 causes the inner end of lever 18 to shift toward the lever 17 and while so shifting it retracts rack bar 26 and as soon as the pin 31 hits the cam portion 30 the teeth on the rack bar will instantly disengage from the teeth on disk 34. Under the tension of spring 46 the disk will turn in the reverse direction from that indicated by the arrow on Figure 1 and thus the auxiliary valve 15 will be automatically closed preventing the escape of the gas through the burner upon resumption of the flow of the gas notwithstanding the fact that the regular valve 14 remains open.

While there is described herein a preferred embodiment of the present invention, it is nevertheless to be understood that minor changes may be made therein without departing from the spirit and scope of the invention as claimed.

What I claim as new is:

1. In combination with a burner and a valve cooperating therewith, a thermostat associated with said burner, means for temporarily holding said valve open, means actuated by said thermostat for releasing the hold of said first mentioned means upon said valve, and a signalling mechanism co-

operating with said first mentioned means and operating instantly upon operation of said second mentioned means.

2. In combination with a burner and a valve cooperating therewith, a thermostat associated with said burner, a disk carried by said valve, a pair of levers, said thermostat being in operative engagement with one of said levers, means adapted to engage said disk preparatory to the expanding action of said thermostat, means associated with the second lever and cooperating with said disk for releasing the engagement of said first mentioned means on expanding of said thermostat, and a signalling device adapted to operate upon disengagement of said first mentioned means from said disk.

3. In combination with a burner and a valve cooperating therewith, a thermostat associated with said burner, a disk carried by said valve, a pair of levers, said thermostat being in operative engagement with one of said levers, means adapted to engage said disk for holding said valve open preparatory to the action of said thermostat, a spring associated with said disk, a rack bar actuated by the second lever upon operation of the thermostat, teeth upon said disk adapted to be engaged by said rack bar, said means being capable of disengagement from said disk when the teeth on said disk come into engagement with said rack bar on expansion of said thermostat, and a signalling device cooperating with said means for giving a signal when said means become disengaged from said disk, said spring being adapted to actuate said disk for closing the valve on contraction of said thermostat.

4. In combination with a burner and a valve cooperating therewith, a thermostat, a disk associated with said valve, a pair of levers, a rack bar carried by one of said levers, said rack bar being adapted to engage said disk for holding the valve open, a rod in operative engagement with the other lever, and means cooperating between said thermostat and said rod transmitting the action of said thermostat upon said rod.

5. In combination with a burner and a valve cooperating therewith, a thermostat, a disk associated with said valve, a pair of levers, a rack bar carried by one of said levers, said rack bar being adapted to engage said disk for holding the valve open on expansion of said thermostat, and means associated with said disk for temporarily holding the valve open preparatory to the action of said thermostat and said rack bar, said means being adapted to be released from said disk on operation of said rack bar.

6. In combination with a burner and a valve cooperating therewith, a thermostat, means cooperating with said thermostat and said valve for transmitting the expanding

or contracting action of the thermostat to the valve, a disk associated with said valve, said disk having off-set and reduced portions, means for engaging said disk for temporarily holding the valve open preparatory to the expansion of said thermostat, said reduced portion facilitating the engagement of said last named means with said disk, teeth upon the off-set portion of said disk, and a rack bar associated with

said first named means, said rack bar being adapted to engage said teeth on expansion of said thermostat for actuating said disk for the purpose of releasing therefrom the engagement of the second named means and for holding the valve open during the expanded state of the thermostat. 15

In testimony whereof I affix my signature.

TEOFIL ZLYDASZYK.
